HERBERT H. WALTERS, OF SYRACUSE, NEW YORK

BREAKER POINT GRINDER

Application filed July 13, 1931. Serial No. 550,483.

This invention relates to a device for grinding the contact points of electric circuit breakers commonly used in the ignition systems of internal combustion engines of motor vehicles.

It is well known that after a short period of use, these contact points become pitted or coated with carbon or oxide to such a degree as to greatly reduce the power efficiency of the engine and that heretofore it has been customary to clean the points with a relatively thin file made for that purpose.

That is, at least one of the point supports is usually pivoted to a suitable support some 15 distance from the point and is spring pressed toward the other point to be opened intermittently by suitable engine driven cams, and when it is desired to clean the points, it is customary to turn the cam to a position which 20 will enable the points to contact with each other under the pressure of the spring at which time the movable contact support may be opened by hand sufficiently to allow the insertion of a file between the points which 25 are then released to allow the spring to force the points into contact at both faces of the file.

The file is then moved back and forth between the points to remove the pits or other 30 accretions thereof, but owing to the fact that the movable point at least is free to move more or less axially, it is evident that this filing action causes the points to be filed more or less rounding or out of parallelism, the 35 result of which is to reduce the sparking efficiency in the ignition system and thereby to reduce the power of the engine.

The main object of the present invention is to avoid these objectionable conditions by 40 the use of a relatively thin rotary grinding disk which may be conveniently inserted between the contact points and rotated at suitable speed to assure the grinding of both points in planes parallel with each other and 45 at right angles to the axes thereof and thereby to maintain the full sparking efficiency in the ignition circuit.

In other words, I have sought to provide 50 a simple and highly efficient grinding unit specifically adapted for grinding the con-

tact points of circuit breakers and capable of being manufactured and sold at a low cost for use by individual car owners and also in public garages, so that the implement as a whole may be stored in compact space as a 55 part of the tool kit of the car ready for use when needed.

Other objects and uses relating to the specific parts of the implement will be brought out in the following description.

In the drawing:

Figure 1 is a perspective view on a small scale of my improved grinding unit showing a portion of an engine and circuit breaker by dotted lines to illustrate the manner of 65 using the implement.

Figure 2 is an enlarged vertical sectional view of a portion of my improved grinder in operative position for grinding the points, taken in the plane of line 2-2.

Figure 3 is a top plate of the circuit breaker shown in Figure 2 together with the adjacent portion of the grinder in operative position.

Figure 4 is a vertical sectional view through 75 the motor case taken in the plane of line 4-4 Figure 6.

Figure 5 is an enlarged detail sectional view taken in the plane of line 5-5, Figure 6.

Figure 6 is a sectional view through the 80 motor case taken in the plane of line 6-6, Figure 4.

Figure 7 is a detail vertical sectional view taken in the plane of line 7-7, Figure 3, showing a portion of the circuit breaker case in elevation partly broken away.

In order that the use of the invention may be clearly understood, I have shown by dotted lines in Figure 1-1 and by full lines in Figures 2-2, 3-3, and 7-7, a portion of 90 a circuit breaker -A- having the usual breaker points or contact members -a- mounted upon suitable supports -b- and -b'-, one of which as -b- is spring pressed by means of the spring -c- toward the other and is adapted to be intermittently opened by means of an engine driven rotary cam -d- shown more clearly in Figure 3.

The grinding unit forming the subject matter of the present application comprises 100

a motor case —1— containing a helical spring motor —2— and a relatively large gear —3— meshing with a pinion —4— which is secured to one end of the shaft —5—.

5 This shaft —5— is journaled at one end in suitable bearings in the motor case —1— to extend axially therefrom, and is adapted to be rotated by the spring motor —2— through the medium of the gears —3— and —4—, the 10 other end of the shaft being provided with a collar —6— splined thereon for axial movement and adapted to receive and support a grinding disk —7— of emery, carborundum or equivalent material, the collar —6— being 15 preferably made in sections, in screw engagement with each other for clamping the grinding disk —7— between them.

The motor case —1— constitutes what may be termed a hollow handle by which the shaft 20 —5— with the grinding wheel or disk —7— thereof may be manipulated for properly adjusting the grinding wheel between the breaker points —a— as shown more clearly in Fig. 7. The larger gear —3— within the 25 handle —1— is secured to a suitable shaft —8— which is journaled in opposite end walls of the handle or motor case —1— for relative rotary movement therein.

The spring motor —2— is preferably of 30 the helical type having its inner end riveted or otherwise secured to the shaft —8— and its outer end attached at a clamping bolt —9— to the peripheral wall of the case —1—. As 35 illustrated, one of the end walls —1'— of the motor case —1— is removable and held in place by clamping bolts —9—, one of which serves as a means of attachment of the outer end of the spring —2— to the peripheral wall 40 of the motor case (see Fig. 6).

40 One end of the shaft —8— is provided with an angular socket —8'— for receiving a suitable key by which the spring —2— may be wound to place it under the desired tension for operating the gears —3— and —4— and 45 shaft —5— together with the grinding wheel —7—.

A brake lever —10— is pivoted intermediate its ends at —10— to the end walls of the motor case —1— within the periphery 50 thereof and has one end extended from its pivot in the direction of rotation and closely adjacent the periphery of the gear wheel —3— and is provided with a brake shoe —11— normally spring pressed against the 55 periphery of the wheel —3— by means of a spring —12— of sufficient tension to cause the brake shoe —11— to normally hold the gear —3— against rotation through the action of the spring motor —2—.

50 The other end of the brake lever —3— is extended outwardly through an opening —13— in the peripheral wall of the motor case —1— and is provided with a handle —14— by which it may be depressed against 55 the action of the spring —12— to release the

gear wheel —3— and thereby allow the motor —2— to rotate the grinding disk —7— through the medium of the shaft —5— and gears —3— and —4—.

An additional brake shoe —15— is mounted upon the inner end of an adjusting screw —16— which in turn is engaged in a threaded aperture in the peripheral wall of the motor case —1— and is provided at its outer end with a handle —17— by which it may be 70 adjusted to bring the shoe —15— into more or less close contact with the periphery of gear wheel —3— so that by properly adjusting the screw —16—, friction of the 75 brake-shoe —15— with the periphery of the wheel —3— may be set to govern the speed 80 of rotation of the wheel and grinding disk driven thereby.

In other words, the brake shoe —15— and its adjusting screw —16— serve as a governor 85 for regulating the speed of movement of the grinding disk through the medium of its driving shaft —5— and gears —3— and —4— when the brake lever —9— is released from its braking position. 9

An additional hollow handle —18— is journaled upon the outer end of the shaft —5— at opposite ends of the collar —6— to assist in properly position the grinding disk —7— between the breaker points —a—, said 95 additional handle —18— being held against axial movement by means of a screw —19— engaging in an annular groove —20— in the adjacent portion of the shaft —5—.

As previously stated, the collar —6— 100 carrying the grinding disk —7— is splined upon the shaft —5— for slight axial movement thereon and for this purpose, the opposite end bearings of the handle —18— on said shaft are arranged in slightly spaced 105 relation to adjacent ends of the collar as shown more clearly in Fig. 7.

The object of this slight axial movement of the grinding disk is to facilitate its entrance between the breaker points —a— when 110 the latter are separated by hand and also to enable the grinding disk to automatically adjust itself axially to rotate in the plane at right angles to the axes of the breaker points or parallel with the meeting faces thereof so 115 as to assure the grinding of both faces in parallel planes.

The supplemental handle —18— is provided with a sight opening —21— in its upper side and also supports a magnifying lens 120 —22— directly under the sight opening, which together with the lens affords a convenient means for visually locating the position of the grinding wheel relatively to the breaker points —a— when adjusting the device for use. 125

Operation

When using this device for grinding the contact points —a— the motor case or hollow 130

handle —1— is held in one hand to support the grinding disk —7— in position for entry between the points —a— while the brake lever —10— is still in its braking position to hold the grinding disk and its driving means against rotation after which the supporting members —b— for the breaker points —a— are separated by hand to enable the grinding disk to be inserted between the points whereupon the member —b— will be released to allow the breaker points to contact with the opposite faces of the grinding disk.

The supplemental handle —18— is then grasped by the other hand of the operator and, with the finger of the hand holding the motor case —1—, the operator may depress the handle —14— of the brake lever to release the brake —11— and thus permit the rotation of the gear —3— by the spring motor —2—, the rotary motion of the wheel —3— being transmitted through the gear —4— and shaft —5— to the grinding disk —7—, which in turn effects the desired grinding of the breaker points —a—, it being understood that the governing shoe —15— will regulate the speed of rotation of the gear —3— and parts driven thereby.

It is evident, however, that in case the brake shoe —11— should fail to hold the wheel —3— against rotation, the brake shoe —15— may be adjusted by means of its screw —16— to effect a positive holding of the gear wheel and parts operated thereby.

It is also obvious that various changes may be made in the detail construction of various parts of the grinding unit without departing from the spirit of the invention.

What I claim is:—

1. A device for grinding the breaker points of electric ignition systems comprising a hollow handle, a spring-motor within the handle, a rotary shaft having one end journaled in the handle, a grinding wheel on the other end of the shaft, and means actuated by the spring-motor for rotating said shaft, said grinding wheel being splined on the shaft for relative axial movement, and means on the shaft for limiting the axial movement of the grinding wheel in opposite directions.
2. In a device for grinding the breaker points of electric ignition systems, a shaft, means for rotating the shaft, a grinding disc splined on the shaft to rotate therewith and for relative axial movement thereon and adapted to be inserted between the breaker points, and a handle having bearings at opposite ends of the grinding disc for receiving adjacent portions of the shaft and for holding the shaft with the grinding wheel thereon in position for grinding the breaker points.

In witness whereof I have hereunto set my hand this 6th day of July, 1931.

HERBERT H. WALTERS.
